UNITED STATES PATENT OFFICE.

CLAUDE D. GRATON, OF NEWARK, NEW JERSEY.

CALENDAR.

Application filed February 28, 1923. Serial No. 621,712.

To all whom it may concern:

Be it known that I, CLAUDE D. GRATON, a citizen of the United States, residing at Newark, in the county of Essex and State 5 of New Jersey, have invented certain new and useful Improvements in Calendars, of which the following is a specification.

My invention relates to an improvement in calendars of a type primarily adapted 10 for use in conjunction with a plan of systematic saving, this plan somewhat paralleling the well-known "Christmas clubs," now run by practically all savings banks.

The main purpose of my invention is to 15 encourage and assist wage earners and salaried people in habits of thrift and systematic saving. Such people are usually paid weekly or monthly. My invention would help these people to deposit at regular intervals, a part of their salary or wage. It also provides a useful calendar for the 20 depositor and an inexpensive advertisement for a bank, trust company, industrial life insurance company, building and loan associations and similar societies, corporations 25 and companies interested in the systematic saving of small amounts at regular intervals.

Other objects of my invention will appear 30 after a consideration of the specification and the accompanying drawings.

In the drawings:

Figure 1 is a plan view of one form of 35 calendar employed by me in my savings plan, and

Figure 2 is a similar view of a modified form of calendar that may be equally as well employed in my savings plan.

Referring to the drawings, and particularly to Figure 1, there is shown a calendar 40 of the monthly type, which embodies a cardboard back 5, formed with the usual opening 6 at its upper end, and adapted to have the name of the bank or other savings institution printed thereon, preferably at 7. On 45 the face of this back 5, there is secured in the well-known manner, the twelve monthly sheets of the calendar, which in this instance, are designated as a whole by the numeral 8.

Formed as an integral part of each of 50 these monthly sheets are stubs or coupons 9. I have shown these monthly sheets as being provided with five of these stubs or coupons, it being of course understood that this number 55 may be increased or diminished so as to provide a stub or coupon for each day in

the month, upon which payments are due. These stubs or coupons are connected to each other as well as to the monthly sheets and through rows of perforations 10, for facilitating the easy detachment thereof.

It is preferable that the day upon which the payments fall due be Monday, and in accordance therewith, each of the stubs or coupons are provided with the dates of the 60 Mondays in the particular month, it being noted that the end coupon has the date of the first Monday thereon, the record coupon, the date of the record Monday, and so on.

Each of these stubs or coupons 9 have 70 printed on their faces, the name of the bank or savings institution fathering the plan of systematic saving, together with the amount of money to be deposited with each stub or coupon, as well as an indicating character 75 for the particular plan being followed. At the space 11 upon the calendar back 5, is the number allotted to the individual depositor following my systematic plan of saving, the said stubs or coupons 9 also 80 bearing a similar number at the space 12.

In Figure 2, there is shown a modified form of calendar that is to be used in a manner similar in all respects to the calendar shown in Figure 1, this modification 85 being in the form of the well-known memorandum or weekly calendar. The same embodies a back 5', having the name of the bank or savings institution thereon. 8' designates the weekly sheets of this calendar, 90 there being obviously, fifty-two of these sheets, and each having printed thereon, alongside the day of the week upon which the deposit is due, the words "Deposit to-day." Each of these weekly sheets have 95 integrally formed upon the lower ends thereof, ordinary bank deposit slips 9', the same being secured to the calendar sheet through rows of perforations 10'. In this modification, the calendar back 5' is also to 100 have thereon the number allotted to the depositor, each of the said deposit slips 9' also bearing this number, as well as the date of the week upon which the payment falls due.

Briefly described the plan of systematic saving with which either one of these calendars are to be used is as follows:

My plan is to be known as the "calendar club" and anyone desiring to join this club 110 designates his intention of depositing 50¢, \$1.00, \$2.00, etc., weekly. Either one of the

calendars shown in the views may be employed in conjunction with this plan, one of these calendars being given to each depositor, the number found upon the calendar being applied to an envelope or file, together with the name and address of the particular member of the club. As each deposit is due, one of the stubs are disconnected from the calendar sheets, these slips or coupons being then taken to the bank, together with the amount of money called for thereon, and are deposited, the slips being filed away by the banking institution in the said envelopes or files. The amounts so deposited are entered in member's bank book. This book bears the same number as the envelope, calendar and deposit slips aforesaid, and identifies such depositor as a member of the "calendar club". The rules governing such club members are printed in said bank book.

The club preferably runs for a year, the nature of the same being such however, as to permit one to join the club any time within the year, in this instance, however, it is necessary that a certain number of the deposit slips or coupons be removed from the calendar employed. As soon as the club year is up, the total amount deposited by each member of the club is ascertained through the number of deposit slips held by the bank as well as by member's deposit book.

When the "calendar club" year or term, as provided in the rules governing members is up, the bank or other institution holding such member's deposit agrees to pay to such

member all, or any part of this deposit together with such interest as may have been agreed upon in the beginning.

I do not wish to limit myself however, to any particular plan, as the same may be improved upon from time to time, the essence of my invention consisting alone of the calendar per se, and further, I do not wish to limit myself to the exact formation of these calendars, as the same may be modified without departing from the spirit and scope of the invention as claimed.

Having thus described my invention, what I claim as new, and desire to secure by Letters-Patent is:—

A depositor's reminder and deposit slip construction comprising a holder including calendar sheets and having an appropriately designated space thereon for the entrance of characters identifying the depositor with his deposits, a group of deposit slips mounted upon each calendar sheet, each of said slips representing a fractional part of the period of time within which the deposits are to be made at intervals in relation to the period of time represented by the respective calendar sheets, each slip being provided with a detachable section, upon which the amount of the deposit may be indicated, and also having an appropriately designated space for the entrance of identification characters corresponding to each other, and the one on the holder.

In testimony whereof I affix my signature.

CLAUDE D. GRATON.
